Filed July 10, 1969, Ser. No. 18,173

Term of patent 14 years

Int. Cl. D15—07

U.S. Cl. D49—14.1

Fig. 1

Fig. 2

Fig. 3

Fig. 4

Fig. 5

Fig. 6

Fig. 7

Fig. 8

FIG. 1 is a front perspective view of a canister vacuum cleaner embodying our new design;

FIG. 2 is a rear perspective view thereof;

FIG. 3 is a front elevational view thereof;

FIG. 4 is a side elevational view thereof as seen from the right in FIG. 3;

FIG. 5 is a top plan view thereof;

FIG. 6 is a rear elevational view thereof;

FIG. 7 is a side elevational view thereof as seen from the right in FIG. 6; and

FIG. 8 is a bottom plan view thereof.

We claim:

The ornamental design for a canister vacuum cleaner or similar article, substantially as shown.
